UNITED STATES PATENT OFFICE

131,472

DESIGN FOR A BADGE OR SIMILAR ARTICLE

John D. Rock, Huntington Park, Calif.

Application November 6, 1941, Serial No. 104,050

Term of patent 7 years

To all whom it may concern:

Be it known that I, John D. Rock, a citizen of the United States, residing in Huntington Park, in the county of Los Angeles and State of California, have invented a new, original, and ornamental Design for a Badge or Similar Article, of which the following is a specification, reference being had to the accompanying drawing, forming part thereof.

Fig. 1 is a face view of a badge or similar article showing my new design.

Fig. 2 is a side elevational view of the article shown in Fig. 1.

Fig. 3 is an end elevational view of said article.

Fig. 4 is a section taken on the line 4—4 of Fig. 1.

Fig. 5 is a slightly enlarged section taken on the line 5—5 of Fig. 4.

Fig. 6 is an enlarged section taken on the line 6—6 of Fig. 3.

The vertical hatching in Fig. 1 indicates the color red, and the horizontal hatching in the same figure represents the color blue.

I claim:

The ornamental design for a badge or similar article, substantially as shown and described.

JOHN D. ROCK.
